UNITED STATES PATENT OFFICE.

CHARLES W. LOGAN, OF KENMORE, NEW YORK, ASSIGNOR, BY MESNE ASSIGNMENTS, TO MARKEL ELECTRIC PRODUCTS, INC., OF BUFFALO, NEW YORK, A CORPORATION OF NEW YORK.

DESIGN FOR A WALL PLATE FOR ELECTRIC-LIGHT FIXTURES.

Application filed December 4, 1926. Serial No. 19,929. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for Wall Plate for Electric-Light Fixtures, of which the following is a specification, reference being had to the accompanying drawing, forming part thereof.

In said drawing:

Figure 1 is a view in front elevation the ornamentation being shown in full in half of the figure and the outline, only, being shown in the other half to indicate the repetition of the ornamentation.

Figure 2 is a side elevation of the same.

I claim:

The ornamental design for a wall plate for electric-light fixtures, as shown.

CHARLES W. LOGAN.
